US0D1081130S

(12) United States Design Patent (10) Patent No.: US D1,081,130 S
(45) Date of Patent:  Jul. 1, 2025

(54) CLUTCH BAG

(71) Applicant: HERMES SELLIER (Société par actions simplifiée), Paris (FR)

(72) Inventor: Pierre-Alexis Dumas, Paris (FR)

() Term: 15 Years

(21) Appl. No.: 35/522,055

(22) Filed: Feb. 22, 2024

(80) Hague Agreement Data

Int. Filing Date: Feb. 22, 2024

Int. Reg. No.: DM/235868

Int. Reg. Date: Feb. 22, 2024

Int. Reg. Pub. Date: Aug. 23, 2024

(51) LOC (15) Cl. 03-01

(52) U.S. Cl.

USPC D3/243; D3/232
